FLOOR WAXER AND POLISHER

Filed Sept. 21, 1931

FIG. 4.

-Inventor-
Leslie M. Appleford

by *MacLennan, Lang and Tansley*
Atty.

UNITED STATES PATENT OFFICE

LESLIE MACPHAIL APPLEFORD, OF HAMILTON, ONTARIO, CANADA

FLOOR WAXER AND POLISHER

Application filed September 21, 1931, Serial No. 564,228, and in Canada June 18, 1931.

My invention relates to improvements in floor wasters and polishers, and the object of the invention is to provide a device of this character particularly designed for containing and distributing fluid wax.

Another object of my invention is to incorporate a fluid wax containing reservoir in the polisher and to furnish such reservoir with a manually controlled fluid wax feeding valve whereby the distribution of the wax upon the floor can be conveniently controlled.

A still further object of my invention is to so construct my polisher that it includes a plurality of waxing and polishing pads, brushes, etc., which are adapted to be detachably secured to the sole plate of the polisher for the various polishing operations.

My invention consists of a floor waster and polisher constructed and arranged all as hereinafter more particularly described and illustrated in the accompanying drawing in which:—

Fig. 1 is a perspective view of my device.

Fig. 2 is a longitudinal vertical sectional view through my device.

Fig. 3 is a perspective view of a plug which I insert in the orifice in the wax distributing pad when the feed valve is removed for replenishing the wax reservoir, and

Fig. 4 is a perspective view of the brush which is adapted to be detachably secured to the sole plate of the polisher.

Like characters of reference indicate corresponding parts in the different views in the drawing.

My device comprises a metal sole plate 1 of substantially flat iron shape, formed upon its upper face with a cylindrical fluid wax reservoir 2.

Centrally of the portion of the plate 1 forming the bottom of the reservoir 2 I provide a fluid wax feeding orifice 3 conically formed at its upper portion 4 to receive a cone shaped valve head 5 formed upon the lower end of a valve rod. Such rod is threaded at its upper portion 6 and contained within a central orifice 7 in the top 8 of the reservoir, a valve actuating handle or hand wheel 9 being secured upon the upper end of the rod. The lower non-threaded portion 11

of the rod is of less diameter than the upper threaded portion 6, so that when such upper threaded portion is unscrewed from out of the orifice 7 the valve rod can be lifted from out of the reservoir. The lower face of the plate 1 is furnished with a waxing pad 14 formed with an orifice 15 underneath the wax feeding orifice 3. This pad is of slightly greater width and greater length than the plate 1 and its ends 16 are lapped over the top of the ends of the plate 1 and secured thereto by a pair of snap studs 17, which enter female stud members 18 in the turned over ends of the pad.

The polisher is furnished with a handle 19 formed at its lower end with a fork member 20 which is pivotally mounted on a pair of trunnions 21 extending outwardly from the sides of the reservoir 2.

In putting the waster in condition for use, the valve rod is unscrewed from the orifice 7 and removed from the reservoir. The fluid wax is then inserted into the reservoir through such orifice. In order to prevent the fluid wax from running out of the reservoir through the orifice 3 I furnish a fabric or metal disc 22 of substantially the same diameter as the orifice 15 in the waxing pad, and such disc is adapted to be temporarily inserted into the orifice 15 so as to close the bottom of the orifice 3 during the filling operation. When the reservoir is filled the valve rod is re-inserted thereinto and screwed downwardly to close the orifice 3, after which the disc can be removed from the orifice 15.

In waxing the floor the hand wheel 9 is turned to unscrew the valve rod to a slight degree, thus lifting the valve head 5 from its seat in the orifice 3. This permits the fluid wax in the reservoir to pass downwardly through the orifices 3 and 15 on to the floor to be distributed by the pad 14.

The threaded portion 6 of the valve rod is a comparatively loose fit within the threaded orifice 7 so that when the rod is loosened to open the orifice 3 for the flow of fluid wax, air can enter the reservoir through the orifice 7. After the wax has been distributed upon the floor the valve rod is rotated to close the

orifice 3, and the pad 14 is replaced by a polishing pad, or by a brush.

The brush 23 illustrated in Fig. 4 is of the same shape as the sole plate 1, being a little larger in size and formed with an upturned lip 24 whereby a sole plate receiving depression 25 is formed in the top of the brush. The top of the brush is preferably made of metal to give added weight and furnished with a bumper pad 26 around the side thereof. The brush is secured to the sole plate 1 by a pair of fabric or leather flaps 27 which are provided with female stud members 18 for engagement with the male stud members 17 upon the top of the sole plate.

When the polishing of the floor is completed with the brush, a final finish may be given through the use of a suitable polishing medium, such as a lamb's wool pad which can be either positioned underneath the brush and slid over the floor or can be used to replace the brush and be secured to the sole plate in the same manner as the waxing pad 14.

From the foregoing description it will be apparent that I have produced an extremely simple and yet effective waxer and polisher for the use of fluid wax, in which the various waxing and polishing pads, brushes etc., can be quickly attached and removed without the exercise of any skill upon the part of the operator, and although I have shown and described a particular embodiment of my in-

vention it is to be understood that I can make such changes and alterations as I may from time to time deem necessary without departing from the spirit of my invention as set forth in the appended claims.

What I claim as my invention is:

1. In a floor waxer and polisher, the combination with a wax distributing pad positioned upon the under face of the polisher, and a fluid wax reservoir incorporated in the polisher and having an orifice communicating with an orifice in the pad, of a valve controlling the flow of fluid wax through the orifice in the reservoir, and a removable valve actuating rod extending upwardly from the valve and threaded through a filling orifice in the top of the reservoir.

2. In a floor waxer and polisher, the combination with a wax distributing pad positioned upon the under face of the polisher and a fluid wax reservoir incorporated in the polisher and having an orifice communicating with an orifice in the pad, a needle valve seat formed at the inner end of the reservoir orifice, a needle valve seating upon the valve seat, and a removable valve actuating rod of enlarged diameter at its upper end and having such enlarged diameter portion threaded through a filling orifice in the reservoir, the needle valve being carried upon the lower end of the rod.

LESLIE MACPHAILL APPLEFORD.
